UNITED STATES PATENT OFFICE.

THOMAS P. TAYLOR, OF BRIDGEPORT, CONNECTICUT.

DESIGN FOR A NECK-RUFF FORM.

No. 39,716.

Specification for Design.

Patented Dec. 22, 1908.

Application filed August 4, 1908. Serial No. 447,000. Term of patent 14 years.

To all whom it may concern:

Be it known that I, THOMAS P. TAYLOR, a citizen of the United States, residing at Bridgeport, in the county of Fairfield and State of Connecticut, have invented a new, original, and ornamental Design for a Neck-Ruff Form, of which the following is a specification, reference being had to the accompanying drawing, forming a part thereof.

The accompanying drawing is a perspective view of a neck ruff form showing my new design.

The salient features of my new design are the circular shape of the neck ruff form with a plain inside edge, and the radially disposed cog-like projections which extend from the outer edge of said form.

I claim—

The ornamental design for a neck ruff form, as shown and described.

THOMAS P. TAYLOR.
